UNITED STATES PATENT OFFICE.

WEBSTER JUNK, OF MOUNT STERLING, OHIO.

SHOCK OR BUNDLE COMPRESSOR.

SPECIFICATION forming part of Letters Patent No. 352,758, dated November 16, 1886.

Application filed February 11, 1886. Serial No. 191,633. (No model.)

To all whom it may concern:

Be it known that I, WEBSTER JUNK, a citizen of the United States, and a resident of Mount Sterling, in the county of Madison and State 5 of Ohio, have invented certain new and useful Improvements in Shock or Bundle Compressors; and I do hereby declare that the following is a full, clear, and exact description of the invention, which will enable others skilled in the 10 art to which it appertains to make and use the same, reference being had to the accompanying drawings, which form a part of this specification, and in which—

Figure 1 is a perspective view of a shock being compressed by my improved shock or bundle compressor. Fig. 2 is a similar view of device detached, and showing the serrations in the ends of the plates in dotted lines. Fig. 3 is a rear view of the frame.

20 Similar letters of reference indicate corresponding parts in all the figures.

My invention has relation to devices for compressing bundles or shocks of straw, corn, or fodder, or similar bundles preparatory to 25 binding them; and it consists in the improved construction and combination of parts of the same, as hereinafter more fully described and claimed.

In the accompanying drawings, the letter A 30 indicates a frame formed by a piece of thick metallic wire or a metallic rod, and this rod is bent to form a cross-piece, B, from the ends of which two longitudinal pieces, C C, project, the ends of which are formed into hooks 35 or eyes D and E, one being preferably a closed eye, while the other is a hook, although both may be hooks or both eyes, if desired.

The inner ends of two flat plates, F F, are 40 cut away and bent to form transverse eyes G G, each eye being of a width nearly equal to one-half of the length of the cross-piece, and these eyes fit and turn upon the cross-piece, and a spring, H, is coiled around the cross-piece at its middle, and has its ends I I bearing 45 against the outer edges of the cut-away portions of the pawls. A rope, J, may pass through the eyes and may be held by the spring-plates, which will bear with their ends against the rope, the ends of the plates nearly covering 50 the eyes or hooks.

If desired, the ends of the plates may be ser-

rated, as at e, Fig. 3, for the purpose of affording a more perfect bite upon the rope.

When the device is to be used, the hooked end of the frame, the frame being preferably 55 formed with one eye and one hooked end, is secured to a stick or rod, which will support it, and the end of the rope is passed through the eye of the frame under the end of the plate, which will hold that end of the rope. The 60 rope is now carried around the shock or bundle, whereupon the free end of the rope is inserted into the hook, in which the other plate will retain the rope. When now the frame and its plates are held against the shock or 65 bundle and the ends of the rope are simultaneously grasped and drawn out, the shock or bundle will be compressed and the ends of the rope will all the time be held firmly from slipping back by the plates, so that the person 70 compressing the shock or bundle may stop during the operation of compressing it and renew his hold, or stop for any other purpose, without any danger of the rope slipping back.

The ends of the spring coiled around the 75 cross-piece of the frame will bear equally as hard against each of the outer ends of the plates, and will bear sufficiently hard against the pawls to hold the rope which is drawn by the expansion of the shock or bundle, to further 80 draw the ends of the plates toward the hook and the eye, and if the ends of the plates are serrated the rope will be held still more firmly without any danger of the rope slipping out of the hook and eye.

85 Although the frame may be made with two eyes or with two hooks, it is most desirable to have one hook and one eye, inasmuch as the end of the rope to be held while the other end of the rope is passed around the shock or bundle will be more securely held by an eye than by a hook, and the hook will afford an easier passage for the insertion of the rope after it has been passed around the shock and partly tightened than the eye, so that it will be seen that 90 it is the most desirable construction to have the hook at one end and the eye at the other end of the frame.

The device may be used for binding or compressing shocks of corn or fodder and 95 bundles of hay, straw, or similar bundles, as well as for compressing and holding any rope

which may be passed around any yielding article, or for holding the ends of a cord or rope passed around an article and desired to be held firmly at the ends.

5 The entire device may be made at a very slight expense, and will be very simple in construction, so that it will be simple in operation and durable, being not liable to get out of order during use.

10 Having thus described my invention, I claim and desire to secure by Letters Patent of the United States—

15 1. In a compressor or binder for shocks or bundles, the combination of a frame consisting of a cross-piece and two longitudinal pieces, plates pivoted at the cross-piece and having their ends bearing against the ends of said longitudinal pieces, said pieces being provided with bent ends for securing a rope, a spring 20 bearing with its ends against the outer sides of the plates and secured to the cross-piece, and a rope or cord, as and for the purpose shown and set forth.

2. In a compressor or binder for shocks or bundles, the combination of a frame consisting 25 of a cross-piece and two longitudinal pieces projecting from the ends of the cross-piece, and provided at their ends, one with an eye and one with a hook, two flat plates having their inner ends cut away at one-half their 30 width and bent to form transverse eyes turning upon the cross-piece, a spring coiled at its middle around the middle of the cross-piece and bearing with its ends against the outer cut-away ends of the plate, and a cord or rope 35 passed through the eye and hook, and clamped by the plates, as and for the purpose shown and set forth.

In testimony that I claim the foregoing as my own I have hereunto affixed my signature 40 in presence of two witnesses.

WEBSTER JUNK.
